KENT A. HAWLEY, OF BALTIMORE, MARYLAND, ASSIGNEE TO LOCKE INSULATOR CORPORATION, OF BALTIMORE, MARYLAND, A CORPORATION OF MARYLAND

RELEASING CLAMP

Application filed July 11, 1929. Serial No. 377,565.

The invention relates to means for suspending the conductors of current transmission lines and has special reference to suspension clamps.

It is well known that it is customary to support transmission line conductors by means of clamps located at the bottom of strings or chains of insulators which are in turn hung from towers located considerable distances apart. It is a fact that snow or ice and sleet frequently collects on the conductor at one side of a point of suspension but not on the other side as for example at the edge of a storm area or when there are differences in temperature or other climatic conditions along the line. Furthermore it frequently occurs, especially in mountainous sections that one or more spans of the conductor may be subjected to the influence of high winds. In either event, and under other circumstances of a more or less analogous nature which may readily suggest themselves, it is apparent that there is an excessive strain at one side of a supporting tower and unless the tower is of excessively heavy construction, that is to say heavier than would reasonably be provided, there is a certain danger that the tower may be pulled out of plumb. Of course under such circumstances the insulator strings are also pulled out of place and damage thereto may easily occur.

It is with the above facts in view that I have devised the present invention which has for its general object the provision of a conductor clamp capable of automatically releasing or at least decreasing its grip upon the occurrence of an excessive strain at one side or the other of the clamp and whatever support it is hung from.

An important object of the invention is to provide a releasing clamp which will under ordinary conditions exert a powerful clamping action upon the cable but which is so constructed as to permit the cable to slip through until the strains have become equalized.

Another object is to provide a releasing clamp of this type which may regain its clamping ability or re-exert its clamping action upon the cessation of the abnormal strain

previously operating to bring about the releasing action.

Another important object is to provide a clamp embodying cam means for effecting the release. 55

Yet another object of the invention is to provide a clamp having an element adapted to be temporarily distorted so as to release the grip upon the conductor so that the latter may slip through and adjust itself, it being also a feature that the distorted element may reassume its natural or normal condition so that the device may regain its clamping function without it being necessary to make any repairs or replacements. 60 65

Another important object of the invention is to provide a clamp of this type which does not depend on springs for its holding action but which has, on the contrary, positive means for applying a clamping force to the conductor. 70

An additional object is to provide a device of this type which will consist of but a few parts, certain of which are more or less standard among insulator manufacturing companies, and which will consequently be inexpensive to make in addition to being easy to apply or install, positive in action, efficient and durable in service, and a general improvement in the art. 75 80

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of my clamp showing it in normal position upon a conductor, 90

Figure 2 is a similar view with parts broken away and in section but showing the releasing action,

Figure 3 is a view partly in end elevation and partly in central cross section, 95

Figure 4 is a detail plan view of the upper clamping member alone,

Figure 5 is a side elevation thereof. 100
Referring more particularly to the draw-

ing, it will be observed that I have shown a clamp for supporting a conductor 1, the clamp embodying a main or lower clamping member 2 having a transversely curved seat 3 for the conductor, this seat being, moreover, curved longitudinally so that the ends thereof will flare away from the conductor to avoid bringing any bending strains thereon such as might occur in the event of swaying or vibration of the conductor. This lower clamping member 2 is represented as provided at opposite sides with bosses 4 having vertically extending holes 5 therethrough for the reception of bolt means to be described. At its center the member 2 is shown as provided with opposed laterally extending trunnions 6 which are preferably integral and which are represented as having downwardly elongated heads 7.

20 Cooperating with the lower member 2 is an upper clamping member 8 of general elongated form with a transversely curved central seat or channel 9 contacting with the conductor 1. The end portions of the member 8 may be considerably reduced in thickness as illustrated at 10, the purpose being to provide a limited flexibility or yieldability of the extensions with respect to the body or major portion of the upper member 8.

25 The holding means is here represented as comprising U-bolts 11 which overlie the reduced extensions 10 and which have their shanks passing through the holes 5 and provided with nuts 12, it being preferable to interpose spring washers 13 between the nuts and the undersides of the bosses 4 to prevent accidental unscrewing of the former.

30 The suspension means is here represented as comprising a pair of links 14 straddling the member 2 and formed with elongated openings 15 for the passage of the trunnions 6, the downwardly prolonged heads 7 of these trunnions projecting beyond the lower ends of the openings 15 so as to prevent lateral displacement of the links with respect to the clamp when in service. At their upper ends the links may be apertured at 16 for connection with a suspension element, not shown, at the lower end of a string or chain of connected insulators. The axis of the trunnions 6 is preferably at substantially the longitudinal center of the conductor, which is the logical and most advantageous location of the pivot. Above the openings 15 the links 14 are provided at their inner faces with flat ledges or shoulders 17 which cooperate with pairs of lugs 18 which project laterally from the opposite edges of the upper clamping member 8.

35 The device is applied to the conductor by placing the clamping members 2 and 8 below and above the conductor and applying the U-bolts 11. Suspension is effected by engaging the links 14 upon the trunnions 6

and then connecting the links with the insulators from which the conductor is to be suspended. When the nuts 12 are tightened the upper member 8 will be drawn down into clamping relation to the member 2 and conductor 1 so that there will be an adequate grip upon the conductor. Under normal circumstances the ledges or shoulders 17 are spaced slightly below the lugs 18 as clearly indicated in Figure 1.

40 In the operation, let it be assumed that an unusual strain comes upon the conductor at one side of the clamp. The first result will be to swing the insulator string, not shown, sideways, the links 14 of course swinging out of a vertical position in a corresponding manner. As rocking movement of the links 14 occurs one end of the ledges or shoulders 17 thereon will engage against one pair of lugs 18 and will exert a strong upward thrust thereon tending to move the adjacent extension 10 of the upper clamping member upwardly. As the extensions 10 are reduced or otherwise formed to possess flexibility, the result will be that the intermediate portion of the upper clamping member will be flexed upwardly, the other extension 10 fulcruming within the other U-bolt. Clearly, this will relieve the clamping pressure of the clamping member 8 upon the conductor 1 so that the latter may slip through the clamp until the strains at opposite sides of the clamp have become equalized. This action will of course occur all along the line until the excessive strains at any points have been eliminated, thereby permitting the different insulator strings to return to normal position. When the string in question resumes its normal vertical position the links 14 will likewise return to vertical position, the shoulders 17 then disengaging the lugs 18 and relieving the strain on the previously flexed member which may then return to normal position exerting its clamping action.

45 From the foregoing description and a study of the drawing it will be apparent that I have thus provided a very simply constructed and easily installed clamp which will have the necessary holding action under normal conditions and which will be capable of automatically releasing in the event of an unusual strain coming upon the conductor at one side or the other of the clamp. It is believed that the construction, operation and advantages will be readily apparent to one skilled in the art without further explanation.

50 While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the

spirit of the invention or the scope of the claims hereunto appended.

Having thus described the invention, I claim:

- 5 1. In combination, a clamping member adapted to support a conductor, a suspension means for said clamping member, a second clamping member, bolt means connecting said clamping members, and means located 70 above the conductor engaging portion of the second clamping member and cooperating between the suspension means and the second named clamping member for distorting and decreasing the holding action of the latter.
- 15 2. A clamping device of the character described, comprising a pair of clamping members adapted for disposition upon a conductor, bolt means securing said clamping members together, suspension means, and co- 75 operating means on the suspension means and one clamping member for distorting the same and decreasing the holding action of the latter. 80
- 25 3. In a clamp of the character described, the combination of a pair of clamping members disposable upon a conductor, bolt means securing said members in clamping relation upon the conductor, suspension means connected with one of said clamping members, 90 and cooperating means on the suspension means and the other of said clamping members for distorting the latter and decreasing the clamping action thereof. 95
- 35 4. A clamp of the character described comprising lower and upper clamping members, bolt means for securing the clamping members in clamping relation upon a conductor, suspension means pivotally connected with the lower clamping member, and cam means 100 on the suspension means cooperating with the upper clamping member at a point spaced from its center to move the same upwardly at one end thereof with the other end fulcruming within one of the bolt means.
- 45 5. A clamp of the character described comprising a lower clamping member having bosses thereon, an upper clamping member having lateral projections at opposite sides of its transverse center, bolts passing through 105 the bosses and each embracing the upper clamping member for maintaining both clamping members in clamped engagement upon a conductor, suspension links pivotal- 110
- 50 ly connected with the lower clamping member, and cam elements on the suspension links engageable with one or the other of said lateral projections upon pivotal movement of the links with respect to the clamp beyond a predetermined extent for forcing one end portion of the upper clamping member upwardly. 115
6. A clamping device of the character described comprising a pair of clamping members adapted for disposition upon a conductor, means securing said clamping members together, suspension means, and cooperating means on the suspension means and one clamping member for distorting the same and decreasing the holding action upon swinging movement of the device beyond a predetermined extent. 120
7. A clamping device of the character described comprising a plurality of clamping members disposable upon a conductor, means securing said clamping members together, suspension means pivotally connected with the assembled clamping members, and means operable upon relative pivotal movement of the suspension means and assembled clamping members for flexing one of the latter and decreasing its holding action. 125
8. A clamping device of the character described comprising a plurality of clamping members disposable upon a conductor, means securing said clamping members together, suspension means pivotally connected with the assembled clamping members, and means operable upon relative pivotal movement of the suspension means and assembled clamping members for flexing one of the latter and decreasing its holding action, said securing means remaining fixed. 130
9. A clamping device of the character described comprising an assembly of clamping members disposable upon a conductor, means securing said clamping members permanently together, suspension means pivotally supporting the assembly, and means operable upon relative swinging movement of the suspension means and assembly for flexing and distorting one end of one of the clamping members and thereby reducing the clamping action of the assembly. 135

In testimony whereof I affix my signature.

KENT A. HAWLEY.
